INDUSTRIAL FURNACE AND FIRING APPARATUS

James M. Guthrie, Allison Park, Pa., assignor to
Frederick S. Bloom, Pittsburgh, Pa.

Application December 2, 1942, Serial No. 467,586

4 Claims. (Cl. 158—7)

1

My invention relates to furnaces, boilers, lehrs, and other equipment heated by the combustion of fuel, and particularly to pre-mix firing systems therefor. A pre-mix firing or combustion system consists in apparatus that mixes the air and fuel for combustion in predetermined proportions at a mixing station remote from the combustion chambers of the furnaces, or other equipment in which combustion is to be maintained.

It has long been realized that more accurate combustion control and better fuel economy can be obtained through the use of pre-mix firing systems, but the fact is that such systems have hitherto been dangerous, this being for the reason that the mixture of air and fuel is essentially an explosive mixture, which is particularly hazardous when it is confined, as in practice it must be confined, in ducts leading from the mixing station to the point or points at which combustion is to be maintained. The patented art in this field attests to the efforts that have been made to eliminate the danger inherent in the operation of such firing systems.

More particularly, my invention is centered in an improved burner for use in pre-mix firing systems. The burner of the invention is provided at its outlet with a valve adapted automatically to close when the pressure of the combustible mixture drops to a value at which there is danger of backfire. Additionally, the burner includes a trap which closes in case a backfire occurs within the burner structure, the closed trap preventing the spreading of the explosion to the ducts that supply the mixture to the burner. Thus, it will be understood that my burner is characterized by a double safeguard against backfiring.

In the accompanying drawings, Fig. I is a dia-grammatic view in side elevation of an industrial furnace equipped with a typical firing system in which my burner may be employed, to provide an organization of the invention defined in cer-tain of the appended claims. And Fig. II is a view in vertical section of an exemplary form of my burner, the wall of the furnace and the supply duct of the pre-mix firing system with which the burner is organized being shown fragmentarily.

The patented art contains several pre-mix combustion systems in which my burner may be used to obtain the advantages in mind. Prefer-ably, if not essentially, the firing system in which my safety burner is used will itself include one or more devices functioning to safeguard the sys-tem against conditions which might lead to an explosion. The backfire-neutralizing means of my improved burner, brought into functional associ-

2

ation with conventional protective or safety de-vices for firing systems, afford a solution of the problem.

On September 22, 1942, Letters Patent of the United States, Nos. 2,296,255 and 2,296,256, were granted for improvements in pre-mix firing sys-tems to one Frederick S. Bloom, the assignee of record of the invention herein disclosed. The fir-ing systems illustrated and described in such Letters Patent embody devices intended to safe-guard the systems against the danger of backfir-ing, and it is in such safeguarded systems that my burner is particularly, though not exclusively, serviceable. While the firing systems shown in these Bloom patents are considered in and of themselves to be perfectly adapted for certain conditions of service, there are cases in which the added safety of my improved burner is desirable—in some cases indispensable. For purposes of il-lustration, I shall herein describe my invention as it may be incorporated with the pre-mix firing system of Bloom Patent No. 2,296,256.

Referring to the drawings, the reference nu-meral 1a is applied to a furnace, or a lehr, for heating or heat-treating articles formed of metal, glass, or other material. A line of burners 2 is mounted on each of the opposite side walls of the furnace, and in service these burners are adapted to project burning columns of fuel and air into the furnace chamber. A supply duct 3a delivers a combustible mixture of air and fuel (the fuel in this case being a combustible gas) into a manifold 4a, and from the manifold the mixture is fed through branch pipes 40 to the burners. More specifically, gaseous fuel is deliv-ered, under superatmospheric pressure, from a pipe 6 into duct 3a, and air is supplied to the duct, by means of a blower or fan 5, and the mixed air and fuel are delivered from the duct 3a to the burner-feeding manifolds 4a on the opposite sides of the furnace.

The firing or combustion system comprises means for establishing and automatically main-taining at predetermined value the ratio of air to fuel in the mixture, and such means, including a piece of apparatus 100 obtainable on the open market under the name Askania ratio regulator, are fully described in said Letters Patent No. 2,296,255. To those skilled in the art it will suf-fice to say that the duct leading from the blower 5 includes an orifice plate 11 and the fuel line 6 an orifice plate 12; that leads 13 and 14 establish communication between the regulator 100 and the pipes 3a and 6 at points on opposite sides of the orifice plates, as shown; that a butterfly valve

7 is arranged in the fuel pipe 6 on the upstream side of the orifice plate 12; that the plunger 9 of a pneumatic cylinder 10 is connected to swing such valve; and that leads 17 and 18 extend from the regulator to the opposite ends of said cylinder. The regulator 100 operates in known way to vary pneumatic pressures in the two leads 17 and 18 in accordance with variations in the pressure differential between the fuel and the air supplied to the duct 3a, and, as the difference between the pressures in said leads rises and falls, the plunger 9 shifts in the cylinder 10 in one direction or the other, correspondingly swinging the valve 7 in the fuel line 6 towards open or closed position. In such manner the ratio of air to fuel in the mixture in duct 3a is established and maintained at optimum value, regardless of fluctuations in the supply pressures of the air and fuel, and irrespective of the usual variations in the demands or requirements of the furnace. The air and fuel are thus mixed in proportions that will afford highest efficiency of combustion and greatest economy of fuel, but it will be understood that such a mixture within a closed firing system is explosive and dangerous.

The burner included in the pre-mix firing system embodies several features of design and operation common to the burners of the above-noted Bloom patent. Turning to Figure II, the burner of my invention will be understood to comprise a metal body 28 that includes a valve-chest or chamber 82. The burner is adapted to be mounted on the side wall of the furnace, as shown, with the outlet orifice or mouth 29 of the burner in registry with the outer and smaller end of a conical passage 30 in a refractory port-block 31 which is, as usual, embodied in the furnace side wall. The combustible mixture of fuel and air enters the chest 82 by way of one of the branch pipes 40 leading from manifold 4a, and within the chest a valve 32 is arranged to control the mouth or orifice 29.

In service the combustion of the gaseous mixture streaming through orifice 29 and port-block 31 into the furnace is initiated in the conical passage 30 in the port-block, and so long as the velocity of the streaming gases is above a critical value, there is no danger of the flame burning back through the orifice 29 and causing premature combustion and explosion in the burner body 28 and branch pipe 40. With this circumstance in mind, it is to be understood that the burner structure includes, advantageously, means for adjusting the valve 32 in accordance with variations in the pressure of the combustible mixture supplied to the burner, so that, regardless of the pressure at which the combustible mixture enters the burner, the velocity of flow through the orifice 29 will either be held above critical value, or the valve 32 will shift into position entirely to close the orifice or mouth of the burner.

Such means may consist in a flexible diaphragm 33, to which the stem 34 of valve 32 is secured. A spring 35, whose effective force may be adjusted by means of a screw 36, bears upon one side of the diaphragm, and tends to shift the rod 34 in right-to-left direction and to move the valve 32 towards closed position, while the pressure of the combustible mixture, transmitted through a passage 66 in a partition 37 in the valve-chest, is effective on the opposite side of the diaphragm, and, opposing the force of spring 35, tends to move the valve away from the mouth or orifice 29. As in service the pressure of the combustible mixture supplied to the chest rises

or falls (other things being equal), the valve 32 is shifted to the right or to the left, and accordingly increases or decreases the effective area of the orifice 29, with the consequence that the velocity of the gases flowing through the port-block 31 is maintained above critical value—above the value at which the flame can work back through the orifice 29 and cause an explosion in the burner body 28.

If the pressure of the combustible mixture should drop to a value at which a safe velocity through orifice 29 cannot be maintained, the valve 32, under the urging of spring 35, moves into fully closed position, and in such position the valve is effective to prevent explosive back-firing. It is merely a matter of properly adjusting the effective force of spring 35 to insure that the valve shall close before the danger point is reached. The body of the valve, it is to be noted, includes one or more small passages 38, which, when the valve is in closed position, permit the flow of a slight but sufficient quantity of the combustible mixture into the throat 30 of the port-block, to sustain a pilot flame.

The valve 32 is arranged to control the flow of the combustible mixture, not at some point in the line of flow removed a substantial interval from the inlet end of the passage 29, 30, but immediately at the inlet end of such passage and preferably immediately at the inlet end 30a of the conical throat of the port-block 31.

A pipe 39 opens through the burner wall, and through such pipe (as presently will appear) air or other fluid under pressure is supplied to the diaphragm chamber within the burner, on opposite side of the diaphragm 33 from that upon which the pneumatic pressure of the combustible mixture is effective. By regulation of the pressure of the air in line 39, the position of the valve 32 may be adjusted, the pneumatic pressure thus established on the right-hand side of the diaphragm supplementing the pressure of the spring 35. Indeed, in some cases the spring may be dispensed with, leaving the valve-shifting diaphragm responsive solely to pneumatic pressures.

Other known pressure-operated devices than flexible diaphragms may be arranged to shift the burner valves in the desired manner, such as the Sylphon illustrated and described in the said Bloom patents.

The rate of combustion is regulated in such manner as to maintain the desired temperature conditions within the furnace. In the exemplary apparatus herein disclosed the rate of combustion is controlled by the same valve 32 as serves to safeguard the burners from back-firing, means being provided for shifting the valves towards or away from their seats 29 according as the temperature within the furnace rises or falls from a critical or predetermined value. The means for so shifting the valves in this case are pneumatic, and are adapted automatically to vary the differential pressure on the valve-shifting members 33 within the burners.

The air-control pipe 39 of each burner is connected by a lead 41 to a pyrometer 24a, which is in turn connected by a lead 25b to a pipe 25a that leads from a supply of compressed air (not shown). A thermocouple, 26a, exposed to the temperature within the furnace, is connected to the pyrometer. In the illustrated furnace it is desirable to provide different temperatures at various points in the length of the furnace, and in such an installation, the burners are arranged 75 in groups longitudinally of the furnace, and a

pyrometer 24a and a thermo-couple 26a are provided for each group. The burners 2 of the furnace 1a are shown to be arranged in three groups of three burners each, and the pneumatic control pipes 39 of the burners in each group are connected in common to the control pipe 41 of a pyrometer 24a. The pyrometers include valves (not shown) that open and close in response to the increase and decrease of the thermo-electric currents in circuits 21a, and, as such valves in the pyrometers open and close, the fluid pressure in pipes 41 leading to the valve-controlling diaphragms 33 (which diaphragms are exemplary of the several types of pneumatic motors that may be used) correspondingly rises and falls; that is to say, as the temperatures rise or fall (in the regions of the furnace into which thermocouples 28a extend) the pressures on the right-hand faces of the burner diaphragms increase or decrease relatively to the pressure of the combustible mixture on the left-hand faces of the diaphragms, and in consequence the burner valves are shifted either towards closed positions or into more widely opened positions. Thus the quantity of the fuel and air mixture delivered into the furnace is regulated. In organizing the burners in groups severally controlled by pyrometers that are individually responsive to thermocouples arranged at successive points longitudinally of the furnace, the temperatures at such points or regions of the furnace may be accurately maintained, and the desired temperature gradient in the furnace may be established and held.

The apparatus admits of great versatility in the matter of temperature regulation. The grouping of the burners may be quickly altered to provide the desired temperature gradient from one end of the furnace to the other; one burner on each side of the furnace may be connected to one pyrometer, and five burners on each side may be connected to another, and so on; indeed, all of the burners may be connected to a single pyrometer, if the conditions should require a single control. This interchangeability of burner grouping is made practical and economical, due to the ease with which the small tubing 38, 41 may be taken apart and re-connected in such way as to provide the desired burner grouping.

An automatic valve 42 is arranged in the fuel supply line 6. If for any reason the pressure of the air, or of the combustible mixture, should fall to the danger point the valve 42 closes and completely shuts off the supply of fuel. The fan 5 will continue in operation, and in such case will scavenge the lines 3a and 4a of the combustible mixture therein. The valve 42 is a known type of pneumatically operated valve, adapted in known way to close the fuel line when the pressure of the gases in pipe 3a falls below critical value.

If for any reason it should prove desirable to close down a burner, other than through the operation of the automatic means described, the attendant may do it. That is to say, a branch 43 is provided for the air line 39 of each burner, and this branch is connected to a supply of air or other fluid under a predominating pressure. The branch includes a valve 44 adjacent to the burner, but it will be understood that this valve may, if desired, be located at a remote control station. The valve is normally closed, and the burner functions in the system, as desired. However, if it becomes desirable to shut the burner down, the attendant merely opens the valve, and a predomi-

nating pressure is immediately established on the right-hand face of the diaphragm. The valve 32 is instantly closed. Thus it is that the air line 43 and valve 44 comprise auxiliary means for quickly varying the relative value of the pressures acting on the valve-controlling diaphragm. It will be perceived that the branches 43 of all of the burners of the furnace may be connected through a single valve to the predominating pressure supply, whereby the burners will respond simultaneously to the control of the attendant. In still further refinement the attendant's valve or valves may be automatically operated in response to certain critical pressures or temperatures in the installation, but it is needless to involve this specification with this or other refinements and modifications that the engineer may supply.

Having described a firing system that includes instrumentalities of the sort with which the improvements of my invention are adapted to be associated, I shall now turn to a description of such improvements.

In accordance with the invention each burner 2 includes a trap that serves, in the event of a backfire in the burner, to prevent the spread of combustion to the branch pipe 40 and other parts of the pre-mix firing system. The backfire trap comprises in this case a flap-valve 60 arranged in the line of flow of the combustible mixture between the inlet and outlet of the burner. The flap-valve is pivoted, at 61, to a member 62 secured in the burner wall, to receive in threaded union the delivery end of feed-pipe 40. The member 62 is provided with an annular valve-seat 63 which the flap-valve 60 is adapted, as will appear below, snugly to engage. Normally the flap-valve is, by the impingement of the gaseous mixture streaming through the burner, held away from the seat 63. If required a light spring 64 may be arranged to assist the streaming mixture of air and fuel in normally sustaining the flap-valve in the open position in which it is illustrated.

If the valve 32 should for any reason fail to function in such way as to prevent a backfire within the burner, the gaseous pressure produced by the backfire operates to close the flap-valve 60 upon seat 63 and thus prevent the spread of combustion to the pipe 40. It will be noted that the flap-valve 60 is normally inclined (when in open position) in the burner body that the pressure produced by a backfire through the inlet of the burner is effective instantly to drive the flap-valve to its seat.

Advantageously, means are provided for locking the flap-valve to its seat, once it has been driven there by a backfire, for in such way the flap or disk-valve is prevented from rebounding from its seat in such way that fire momentarily lingering in the burner after the valve has been "slapped" closed cannot spread. Said means may consist in a resilient catch 65 that engages the edge of the flap-valve as it is "slapped" into closed position, and locks the valve to its seat. The catch is manually releasable, so that the flap-valve may, after the occurrence of a back-fire, be reset for normal operation of the burner. Means to this end may comprise a finger 76 that is vertically reciprocable in the member 62. The upper end of the finger is tapered, as shown, so that, when the accessible lower end of the finger is pressed, and the finger moved upward, the catch is engaged and swung into valve-releasing position. The pressure of the combustible mixture in the pipe 40, together with the tension of the spring 64 (if such a spring

is used), is effective to restore the valve to position for normal operation of the burner.

Means are also provided to safeguard the burner body against rupture under the stress of an explosive backfire. Such means comprise essentially a pressure-releasing device which may, as here shown for purposes of illustration, consist in a plate 67 normally closing an orifice 68 in the burner body. The plate 67 is held in hermetic engagement with the wall of the valve body by means of springs 69, and if and when a dangerous pressure is developed within the burner, such as is developed by an explosive backfire, the plate is forced from its seat, and escape is afforded for the gases under excessive pressure within the burner.

The foregoing specification gives a full disclosure of the invention, and it will be understood that various modifications and refinements are permissible within the terms and intent of the appended claims.

I claim as my invention:

1. A pre-mix firing system for a furnace installation including a combustion chamber, a burner, and means for supplying a mixture of air and fuel to said burner, the body of said burner having an inlet for said mixture and an outlet for the passage of the mixture into said combustion chamber, a valve arranged in the burner body to regulate the effective area of said outlet, a pneumatic device, a member connecting said pneumatic device to said valve and being movable to adjust the position of said valve in response to variations in the differential of two pressures acting in opposition on said member, one pressure being the pressure of said mixture, with the effect that the velocity of the mixture streaming into said combustion chamber is normally held at backfire-preventing value, said outlet being disposed adjacent to one end of the burner body and said inlet being disposed between said outlet and said pneumatic device, and a backfire trap disposed across the mouth of said inlet in the line of flow between the inlet and the outlet, said backfire trap being movable into closed position on said inlet under the effect of gaseous pressure acting in reverse direction to the normal line of mixture flow between said inlet and said outlet, said outlet valve being arranged and preconditioned to operate under the effect of said pneumatic device to close said outlet against backfire when the mixture pressure in said burner body drops to critical value, and said trap being arranged and preconditioned to move

into inlet-closing position in the event that said valve fails to move into backfire-preventing position in said outlet.

2. The structure of claim 1, said backfire trap comprising a valve member hinged adjacent to the edge thereof which is nearer to said outlet and adapted to swing on its hinge into outlet-closing position, said last named valve member being inclined from said edge in a direction away from said outlet, substantially for the purpose described.

3. The structure of claim 1, together with manually releasable means for locking said trap in closed position, whereby the burner requires manual attention before the system can be returned to normal operation after the trap has been closed by abnormal conditions within the burner.

4. A pre-mix firing system for a furnace installation including a combustion chamber, a burner, and means for supplying a mixture of air and fuel to said burner, the body of said burner having an inlet for said mixture and an outlet for the passage of the mixture into said combustion chamber, a valve arranged in the burner body to regulate the effective area of said outlet, a pneumatic device, a member connecting said pneumatic device to said valve and being movable to adjust the position of said valve in response to variations in the differential of two pressures acting in opposition on said member, one pressure being the pressure of said mixture, with the effect that the velocity of the mixture streaming into said combustion chamber is normally held at backfire-preventing value and a backfire trap disposed across the mouth of said inlet in the line of flow between the inlet and the outlet, said backfire trap being movable into closed position on said inlet under the effect of gaseous pressure acting in reverse direction to the normal line of mixture flow between said inlet and said outlet, said outlet valve being arranged and preconditioned to operate under the effect of said pneumatic device to close said outlet against backfire when the mixture pressure in said burner body drops to critical value, said trap being arranged and preconditioned to move into inlet-closing position in the event that said valve fails to move into backfire-preventing position in said outlet, and manually releasable means for locking said trap in closed position on said inlet.

JAMES M. GUTHRIE.
